UNITED STATES PATENT OFFICE.

GEORGE J. CLINE, OF GOSHEN, INDIANA.

BARREL-COVER.

SPECIFICATION forming part of Letters Patent No. 393,212, dated November 20, 1888.

Application filed October 8, 1888. Serial No. 237,455. (No model.)

To all whom it may concern:

Be it known that I, GEORGE J. CLINE, a citizen of the United States, residing at Goshen, in the county of Elkhart and State of Indiana, have invented certain new and useful Improvements in Barrel-Covers; and I do declare the following to be a full, clear, and exact description of the invention, such as will enable others skilled in the art to which it appertains to make and use the same.

This invention has relation to devices for securing a trap or cover on the ends of barrels, and is designed to be used on the heads of barrel-churns.

The invention will be fully understood from the following description and claims, when taken in connection with the accompanying drawings, in which—

Figure 1 is a plan view of my improved device, showing the parts in a locked position, and Fig. 2 is a sectional view of the same taken on the line $\alpha-\alpha$ of Fig. 1, showing the same in connection with a portion of a barrel.

Referring by letter to the said drawings, A indicates a portion of a barrel, which may be that of the barrel used in churns.

B indicates an annular top seated at its outer edge or margin in the croze of a barrel, and provided with a central annular aperture, a, which is preferably formed at its mouth with an annular lip, b. This head B is designed to be fixed in the croze of a barrel. Arranged at diametrically-opposite points of the opening a and on the outer side of the head B are loops or staples C, which are designed to receive a lock-bar, as will be presently explained.

D indicates a rotatable cover for the opening in the head of a barrel. This cover is preferably provided on its under side with a marginal annular groove to receive the lip or flange b of the head B. This cover D is furthermore provided on its upper side with a series of lugs which incline to opposite ends from their center. In the present illustration I have shown four of these lugs, E, they being arranged diametrically opposite each other in pairs, for a purpose which will be presently explained.

F indicates a hand-lever. This lever is secured to the upper side of the rotatable cover

D and extends beyond the same at opposite ends, so that it may be grasped at either end. This hand-lever is secured to the cover flush with the lowest point of the inclined lugs or 55 slightly beneath the same, so as to offer no obstruction to the action of the lock-bar.

G indicates a securing-bar. This bar is designed to enter the loops C, and is preferably provided at one end with a stud or lug, d. 60 Secured to the under side of this securing-bar and arranged at right angles thereto is a lock-bar, H, it being fixed to the securing-bar G and designed to move therewith.

I indicates a thumb-screw, which passes 65 through an aperture in both the securing-bar G and the lock-bar H, and may enter the hand-lever F, which is secured to the rotatable cover.

In operation the cover D is placed over 70 the aperture in the head B and the said cover turned so as to have the ends of one pair of the inclined lugs come to the openings of the loops or staples C. The securing-bar G is then placed in the said loops above the cover, 75 so as to have its lock-bar H lie parallel to and above the hand-lever F. The screw I is then applied, so as to prevent the securing-bar and lock-bar from leaving their positions. Then by simply rotating the cover to the right 80 by means of the hand-lever F the lugs will exert an upward pressure against the lock-bar H and by the securing-bar G against the loop C, and consequently an inward or downward pressure of the cover against the head, 85 thereby effecting a tight joint at the opening therein.

It will be observed that while one set of lugs E are pressing against the lock-bar H a corresponding set is acting in a similar manner against the securing-bar G.

Having described my invention, what I claim is—

1. The combination, with a barrel having the head fixed in the croze thereof and provided with a central opening, of the loops secured to the said head at opposite sides of the opening, the rotatable cover having the two sets of inclined lugs on its outer side and a handle fixed thereto, the securing-bar adapted to enter the said loops, the lock-bar secured at right angles to the securing-bar, and the set-screw 95 100

passing through both bars and into the cover or handle thereof, substantially as specified.

2. The combination, with a barrel having the head secured in the croze thereof and provided with an opening, of the loops secured to the said head, a covering for the opening having inclined lugs on its outer side, a securing-bar adapted to enter the loops, and a lock-bar fixed

to the securing bar at right angles thereto, substantially as specified.

In testimony whereof I affix my signature in presence of two witnesses.

GEORGE J. CLINE.
